UNITED STATES PATENT OFFICE

CARLTON A. PRICE, OF LA PORTE, INDIANA

PNEUMATIC BOAT PROPULSION

Application filed June 21, 1929. Serial No. 372,638.

This invention relates to means for propelling boats and has for its primary object the propelling of the boat by pneumatic means. To those well versed in the art the advantages of pneumatic propulsion are well known, and as will be seen by the following description of my invention, I have applied such means in a very simple and efficient form.

In describing my invention reference is made to the accompanying drawing, in which—

Fig. 1 is a side elevation of a boat embodying my invention with fragments removed to disclose the interior construction;

Fig. 2, a front elevation of the boat with part of the hull broken away; and

Fig. 3, a rear elevation of the boat.

Like characters of reference indicate like parts throughout the several views in the drawing.

I form a boat hull 10 with the under side of the after part having substantially an inverted U-shaped cross section, which I shall here designate as a wind or air tunnel 11. This tunnel is entirely open from its under side and likewise is open across the rear end at the stern of the boat.

At the forward end of the boat I position a funnel 12 here shown as opening forward. From this funnel I carry a conduit 13 downwardly and rearwardly to discharge into a second conduit 14 formed along the inner side of the bottom of the hull 10. This second conduit 14 discharges rearwardly into the tunnel 11.

Within the funnel 12, I rotatably mount a propeller 15 which is driven by the engine 16 through suitable driving means here shown as the shafting 17, 18, and the bevelled-gears 19, 20. The boat is provided with the usual rudder 21.

Upon the motor 16 being operated, the propeller 15 is rapidly revolved in a direction which in itself will tend to pull the boat

forwardly. The slip stream from the propeller is discharged rearwardly through the conduits 13 and 14 and on through the tunnel 11. By so discharging the blast from the propeller 15, water, entering into the conduit 14, is forcibly driven rearwardly therefrom and back out through the tunnel whereby the boat will tend to be driven forwardly. While I have here shown and described my invention in the form as now best known to me, it is obvious that many structural changes may be made without departing from the spirit of the invention, and I therefore do not desire to be limited to that precise form nor any more than may be necessary by the following claims.

I claim:

1. In a boat, a hull, means for discharging air under pressure, a conduit along the under side of said boat having a substantial length midship of the boat and adapted to be below the water line of the boat, said conduit being closed except at its front and rear ends, said means discharging air into said conduit, and said hull having an after part of its under side inverted U-shaped in cross-section open from below and from its rear, and said conduit discharging along said after part.

2. In a boat, a funnel located above the hull at the forward end of the boat, a rotating propeller located at the mouth of the funnel, a conduit closed except at its front and rear ends extending for a substantial length midship inside of and along the bottom of the hull, a conduit from the funnel discharging into the forward end of the first conduit, and outside channels in the under side of the after part of the boat into which the first conduit discharges.

3. In a boat, a funnel located above the hull at the forward end of the boat, a propeller located at the mouth of the funnel, means for rotating the propeller, a conduit located within the boat amidship thereof and

extending for a substantial distance longitudinally of and near the bottom of the boat, a curved and tapering conduit extension of the funnel discharging into the first conduit, and aprons longitudinally projecting downwardly from the under side of the after part of the boat, said first conduit being closed except at its intake and discharge ends and discharging between the aprons, a length of 10 said conduit being below the water line of said boat.

In testimony whereof I affix my signature.
CARLTON A. PRICE.
